UNITED STATES PATENT OFFICE

KUWAKICHI FUJITA, OF HAZLETON, PENNSYLVANIA

BURGLAR ALARM

Application filed June 27, 1930. Serial No. 464,292.

The object of this invention is to provide an arrangement embodying some of the features of that disclosed in my United States Patent No. 1,368,791, but including improvements relating to the controlling devices, whereby reliability in operation is assured, without danger of false operation resulting from vibration and the like.

A further object is to provide for the inter-
10 position of safety means adjacent to the ham-
mer exploding the cartridge so that the release
both of the safety means and the cartridge
holder by the completion of an electric cir-
cuit, incident to the forced entry of a build-
15 ing, is required before the hammer is opera-
tive for firing purposes.

A further object is to provide for the elec-
trical control, through a plurality of magnets
and armatures, of mechanical means adapted
20 to retain and release slidable mechanism,
which in turn renders the safety means in-
active and causes the movement of the car-
tridge holding means to operative position
with reference to the hammer.

25 With the foregoing and other objects in
view, the invention consists in the novel con-
struction and arrangement hereinafter de-
scribed, it being understood that modifica-
30 tions may be made within the scope of the
claims without departing from the spirit of
the invention.

In the accompanying drawings forming a
part of this application,

35 Figure 1 shows a portion of a window sash
and frame, in elevation and section, with the
contact means mounted in the window sill,
and housing for the apparatus described be-
low appearing beneath the sill.

40 Figure 2 shows the mechanism in front ele-
vation, the housing being dotted.

Figure 3 is a vertical section on the line 3—3
of Figure 2.

45 Figure 4 is a vertical section in a parallel
plane but the cartridge holder is in lower and
operative position.

Figure 5 is a detail view chiefly in perspec-
tive, showing certain of the arrangements em-
bodied in the assembly.

50 Figure 6 is a detail view, in perspective,
showing the manner in which the upper hook

engages the barrel or cartridge holding de-
vices.

In this application and in the patent above
referred to an alarm is given by the discharge
55 of a cartridge received by a barrel or car-
tridge holding device carried by a pivoted
block, the latter being operated by a heavy
spring when electrically released and causing
60 the discharge of the cartridge by the firing
mechanism.

A base or the like designated 10 may be
considered as an instrument board in this
case, and on the upper portion thereof I
mount a barrel 11 which is received within
65 a barrel holder or block 12, the latter con-
stituting with extension 12' a pivoted brack-
et movable about an axis defined by rod or
shaft 13.

Coiled springs 14 surround the end por-
70 tions of rod 13 and inner spring arms 15 bear
on the base 10. The opposite portion 15' of
each spring arm extends alongside of block
12 and is turned at 16 toward the center and
across the surface of recessed portion 17 of
75 the block. This resilient device effects the
forcible movement of the block from the posi-
tion of Figure 3 to the position of Figure 4,
the latter being the operative position.

The barrel 18 received and held by the
block, is engaged by a pivoted hook 19 mount-
80 ed on bracket 20 secured to the base 10, and
the release of the element 19 by the electric
means described below, is required in order
that the blank cartridge 21 may be exploded
85 by the firing pin 22 designed to engage sta-
tionary hammer 23 mounted in block 24 in
the base 10.

Safety means prevent false discharge of
the cartridge, and involve the provision of a
20 pad or the like 25 which projects beyond the
stationary hammer and which would be en-
gaged by the breach portion of the barrel 18
unless shifted from the dotted line position
of Figure 4 to the full line position thereof.
25 Vibration due to the discharge of any one
piece of apparatus in the system might,
through vibration, effect the other pieces of
apparatus, except for the mechanism just de-
scribed.

The system is connected with the appara-

tus through suitable wires, and terminals 30 and 31, serving an obvious purpose, one of these being connected by wire 32 with magnet 33. This magnet is connected by wire 34 with magnet 35, and the latter is connected by wire 36 with contact numbered 37 cooperating with contact 38 which has connection by means of wire 39 with terminal 31.

Magnet 33 is provided with an armature 40 secured at 41 to a housing 42, the opposite end of the armature being free, and a bracket 43 depending from the armature in position for engagement by the latch arm 44 of an angle lever. The other arm of this lever is designated 45 and is slotted longitudinally for the accommodation of a pin 46 which is movable through the slot and is connected with the offset end 47 of a lever 48, the lever being pivoted at 49. The lever 48 is provided with an upstanding arm 50, and a spring or springs 51 connected with the upper end of arm 50 will also be connected with the stationary member 52. This lever 48 is designed to operate a slidable device carrying lower magnet 35 adapted to release the controlling means described below.

A lower slide 53 mounts a bracket 54, and the latter operates vertically between the guides 55 carried by base 10. Bracket 54 includes an upper horizontal portion to which the core 56 of magnet 35 is directly connected, and the said horizontal portion of the bracket also carries a hook or the like 58 which engages the lever 48, and the lever is forced to an upper position, shown in Figure 2 by the movement of a pin or operating device 59 having an enlarged lower end 60 by which it is controlled. The apparatus is set by hand pressure, in an upward direction exerted upon the end portion 60 of stem or pin 59, resulting in the movement upwardly of the bracket 54, and the elevation of the lever 48, so that the left end of this lever will move to the position of Figure 2, and the angle arm 44, 45 will engage the element 43 of armature 40, providing a form of latch, released when armature 40 is drawn upwardly by the energization of magnet 33 when the contact mechanism of any standard or preferred form, such as that shown in Figure 1, is operated by the opening of a door or window.

The contact mechanism just referred to includes contact elements 64 and 65, and a pin 66 is carried for instance by the window sash 67, the pin or stud 66 normally separating the contacts when the window is closed and allowing spring contact 64 to engage contact 65 when the sash is raised.

Whereas the housing for the apparatus shown in Figures 2, 3 and 4 may be located at a convenient point, I have shown this housing designated 68 in Figure 1 as being positioned beneath the window frame 69. Access

may be obtained to the interior by means of doors 70 and 71.

The alarm circuit may be controlled from a door, skylight, or other part of a building or other structure. 70

Magnet 35 is provided with an armature 75 to be attracted by core 56 and this armature is rigid with reference to hook 76, the latter being pivoted at 77. A stop limits the movement of the hook and armature in one direction and is designated 77. Pressure toward the left in Figure 3 is placed upon hook 76 by means of a spring 78. Slide 53 operating between guides 55 is provided with an opening 53' and this opening is engaged by hook 76 in order to retain the slide in the position of Figure 4. 75

Upper slide 81 operating between guides 82 carries an engaging device 83, and the coiled spring 84 passes beneath element 83 and its opposite ends are secured to the base at 85. This spring tends to hold slide 81 in an upper position so that a cut-away portion in extension 87 on the slide (the opening or cut-away portion being designated 88) cooperates with the right end of pivoted hook 19, as shown in Figures 2 and 3 and also in Figure 4. The fact that the slide is normally moved upwardly by spring 84, insures the engagement of the barrel 18 in the manner shown in Figure 3, so that the explosive device assumed to be received by the barrel is not in position for discharge by the firing mechanism, but the apparatus is primed for operation when contact is made as shown in Figure 1 and the magnets 33 and 35 are energized. 95

The circuit being completed through contacts 64 and 65 by the opening of a window or the like, current flows through wire 32, magnet 33, wire 34, magnet 35, wire 36, contacts 37 and 38, wire 39 to terminal 31. A source of current will of course be included in the circuit, and is not shown in the present drawings. The energization of magnet 33 releases lever 44, 45 when armature 40 is attracted, and the lever 48 drawn downwardly by spring or springs 51, produces the downward movement of lower slide 53. Engagement takes place between hook 58 and the lever 48 so that these elements move together 115 and bracket 54 mounting magnet 35 moves at the same time, and likewise slide 53.

When the lower slide 53 moves downwardly, upper slide 81 also moves downwardly, because engagement between the slides is produced by means of hook 76 as shown in Figure 4. The downward movement of the upper slide 81, in channel member C carries pad 25 downwardly and from the dotted line position of Figure 4 to an active full line position. Slide 81 is guided by stud 23 passing through slot 91. The safety device represented by pad 25 and its operating means, now makes it possible for the firing mechanism to discharge the cartridge 21, when the 120 125 130

barrel 18 and barrel holding device 12 are released by hook 19 which moves to the position of Figure 4, from the position of Figure 3, upon the aforesaid downward movement 5 of slide 81.

Vibration producing the mechanical release of a trip or the like will not operate the alarm, due to the important fact that both magnets must be electrically energized to permit 10 the joint effect of allowing lower slide 53 to descend under spring action (when released at 43) and causing the upper slide to descend because of the electrical control of hook 76 pivoted on the upper side and engaged 15 by the lower slide.

Hooks 76 and 58 do not directly cooperate with each other and are in different planes when looking directly toward base 10 in Figure 3 and in Figure 4.

20 Hook 76 normally held inactive by spring 78 engages the lower slide only when armature 75 is attracted and magnet 35 is energized simultaneously with magnet 33. Hook 76 constitutes an operating element between 25 the slides 53 and 81, and the joint mechanical and electrical features just referred to are of particular importance in rendering the device effective in carrying out the main objects of the invention.

30 Means are provided to break the electric circuit which energizes the electro-magnets when the device has operated. A leaf spring 101 normally maintains a pin 102 in inoperative position. When the block 12 is released, 35 the end of the block 12 adjacent to the rod or shaft 13 will engage the leaf spring 101, thus forcing the pin 102 outward to engage the contact member 38 and move the latter away from the contact 37, thus breaking the circuit.

40 When the block is restored to its operative position the pin will be carried back and the circuit will be re-established.

The hereinbefore described construction admits of considerable modification without 45 departing from the invention; therefore, it is the wish not to be limited to the precise arrangements shown and described, which are as aforesaid, by way of illustration merely. In other words the scope of protection contemplated is to be taken solely from the appended claims, interpreted as broadly as is 50 consistent with the prior art.

Having described the invention, the following is claimed:—

55 1. In an alarm, relatively movable firing means and receiving means for an explosive element, means holding both of said means out of cooperative relation, a slideable element operatively connected with said holding 60 means to release the latter when moved, a safety element carried by said slideable element and movable into and out of operative position to prevent or permit engagement of the explosive element with the firing means, 65 and means for operating the slideable element

to release the holding means and simultaneously shift the safety element out of operative position, the last said means being provided with a remote control by which it is rendered operative.

70 2. In an alarm, spring-actuated receiving means for an explosive element, a firing pin against which the explosive element is driven by the receiving means, a latch for retaining the receiving means spaced from the firing pin, a slide operatively connected with the latch for releasing the latter, a safety element carried by the slide and disposed adjacent the firing pin in one position of the slide to prevent engagement of the explosive element with the pin, and means for effecting movement of the slide to release the latch and simultaneously shift the safety element to a point removed from the firing pin to permit engagement of the pin with the explosive element.

75 3. In an alarm, spring-actuated receiving means for an explosive element, a firing pin against which the explosive element is driven by the receiving means, a latch for retaining the receiving means spaced from the firing pin, a slide operatively connected with the latch for releasing the latter, a safety element carried by the slide and disposed adjacent the firing pin in one position of the slide to prevent engagement of the explosive element with the pin, and means for effecting movement of the slide to release the latch and simultaneously shift the safety element to a point removed from the firing pin to permit engagement of the pin with the explosive element, said last named means having an 80 electro-magnetic release.

85 In testimony whereof I hereby affix my signature.

KUWAKICHI FUJITA.
